(57) **CLAIM**

The ornamental design for the “gas turbine blower/pump,” as shown and described.

DESCRIPTION

FIG. 1 is a perspective view taken from the right front side view of the gas turbine blower/pump;

FIG. 2 is a perspective view taken from the rear right side view of the gas turbine blower/pump;

FIG. 3 is a front elevational view of the gas turbine blower/pump;

FIG. 4 is a left side elevational view of the gas turbine blower/pump;

FIG. 5 is a right side elevational view of the gas turbine blower/pump;

FIG. 6 is a rear elevational view of the gas turbine blower/pump;

FIG. 7 is a top plan view of the gas turbine blower/pump; and,

FIG. 8 is a bottom plan view of the gas turbine blower/pump. The broken lines in FIGS. 1, 2, 3, 4, 5, 6, and 7 depict environment and form no part of the claimed design.

1 Claim, 4 Drawing Sheets

FIG. 4

FIG. 3
